UNITED STATES PATENT OFFICE.

MAX A. ZÜRCHER, OF PHOENIXVILLE, PENNSYLVANIA.

RAILWAY-CAR FRAME.

SPECIFICATION forming part of Letters Patent No. 401,529, dated April 16, 1889.

Application filed July 6, 1888. Serial No. 279,221. (No model.)

To all whom it may concern:

Be it known that I, MAX A. ZÜRCHER, a citizen of the United States, residing at Phoenixville, county of Chester, and State of Pennsylvania, have invented new and useful Improvements in Railway-Cars, of which the following is a specification.

My invention relates to improvements in the construction of railway-car frames, and particularly upon that class of car-frames disclosed in a prior patent granted to me by the United States on the 5th day of June, 1888, No. 384,225, and also upon the invention disclosed in my application for a patent for improvement in car-floor frames, filed May 25, 1888, bearing Serial No. 275,121.

The object of the present invention is, first, to give to the frames of the structures referred to in said patent and application additional strength and rigidity, and, second, to adapt them more fully to cars of special classes and designs. These objects are accomplished principally by first giving increased depth to the several vertical longitudinal trusses at or near the car center, or at the large door, window, or other openings, by curving or expanding either or both of the chords of each of these trusses, or by trussing additionally above or below each or both chords, or any combination of them, thereby enabling the web-shear, due to given strains, to be transmitted around said openings, thus forming a complete and statically-framed truss or trusses, the latter integrally connected together, so as to act as one truss. They are accomplished, secondly, by means of the constructions hereinafter described, and particularly pointed out in the claims which follow this specification. By means of the increased central depth of the trusses I am enabled to construct a double or multiple deck car having the upper compartment or compartments extending the whole length of the car, or a part or parts only thereof. I also diminish the depth of the vertical longitudinal trusses at the ends of a car to a minimum, thereby increasing its rigidity and giving especial strength to the structure to resist the compression from backing of a train and from collisions, as well as the traction strains, thus avoiding telescoping by enabling the top and bottom chords to divide the

impact therefrom more evenly. My improved skeleton car-frame, having increased depth at or near the center, is a statically-constructed hollow body or frame; but the constructions shown in my above-named patent are limited to prisms, because all the various intersections of its longitudinal faces or girders are shown parallel to each other.

My invention will be better understood by referring to the drawings which accompany this specification, and to the claims which follow.

In the drawings like letters of reference wherever used refer to like parts; also, the detail construction of each complete view is generally shown different for each side or end, but may be constructed symmetrically.

Figures 1 to 12, inclusive, are side elevational views representing modified forms of halves of my improved railway-car frames, showing especially the vertical longitudinal side girders. Fig. 13 is a similar view of a whole car-frame. Fig. 14 is a plan view of the horizontal or inclined (or both kinds combined) interior longitudinal trussing along the floor level or levels C, showing various web constructions. Fig. 15 is a plan view of the horizontal or inclined (or both kinds combined) exterior longitudinal trussing along the bottom chords s' of the vertical longitudinal trusses B, F, and r, singly or any or all combined, also showing various web constructions. Fig. 16 is a plan view of the horizontal or inclined (or both kinds combined) exterior overhead longitudinal trussing, along the top chords s of the longitudinal trusses B, following the bottom chords q' of the transverse roof-trusses q, also showing various web constructions. Fig. 17 is a plan view of the inclined or horizontal (or both kinds combined) exterior longitudinal roof-trusses along the same top chords s, but following instead the rafters q⁴ of the same roof-trusses q, also showing various web constructions. Figs. 18 and 19 are exterior side elevational views of half of my double-deck-car frame. Fig. 20 is a sectional transverse interior view of the same. Figs. 21 to 27, inclusive, are sectional transverse interior views having interior longitudinal girders, r. Figs. 28, 29, and 30 are transverse sectional

views showing interior longitudinal girders, F. Figs. 31 and 32 are similar views having a combination of trusses, F and r.

A represents my improved car-frame, of metal or any analogous material which possesses the required strength.

B B represent the exterior side longitudinal trusses of the frame, they being statically constructed with non-adjustable web members 10 extending throughout the entire car-length for all of its essential members, and each one able to resist compression and tension to the required amounts, and having a top chord, s, and a bottom chord, s', each of which chords 15 is continuous throughout each girder length with vertical web posts or struts s², which serve also as members of the transverse vibration trusses. I also provide diagonal web members s³, and when these diagonals intersect each other they may be connected in the usual manner with rivets, bolts, or pins, so as to resist transverse shear, and with or without the plates s⁴, or they may be welded together. These same connections and features, as above stated, are also to be used for 20 all other places and members throughout the whole car-frame.

In Fig. 4 the bottom chords s' are horizontal, and in Figs. 5 to 8, inclusive, and 11 30 they are the same, but additionally trussed underneath to transmit the web-shear past the openings, while in Fig. 1 they are straight but inclined downward toward the center from each end, while in Figs. 2, 19, and 9 to 35 13, inclusive, they are curved or partly so. In Figs. 3 and 18 each is of a polygonal shape. The top chords s in Figs. 18 and 7 to 12, inclusive, are horizontal, while in Figs. 13 and 2 to 6, inclusive, they are curved or partly so. 40 Those of Fig. 1 are straight, but inclined downward from center toward each end, and Fig. 19 of a polygonal shape.

The side trusses, B, as shown in Figs. 13 and 19, each consist of two or more complete trusses, one above the other, so as to have the window, door, or other openings placed between them, the whole rigidly connected together to serve as one truss, wherein vertical posts s² have to act also as girders in the 45 50 longitudinal direction of the car should these spaces not be trussed with diagonals, which may also be the case throughout or through any part of the way; but s² may be then omitted for any or all trussed spaces. These 55 trusses B may be far enough apart to clear the trucks by being outside of the latter, and thereby enable increased depth of the trusses at said locations, and they may be made strong enough so as not to require any interior longitudinal vertical girders, F or r.

As already stated, my car-frame constitutes externally a statically-constructed hollow body or frame, to which I give additional strength by the following interior constructions: First, one or more interior vertical longitudinal trusses or girders, r, extend the whole 60 or any part of the length of the car; or they may

be same as the trusses B, extending any or all the way to the roof, and of similar constructions able to fulfill all functions, as fully explained in my Patent No. 384,225, marked therein F, Figs. 28, 29, and 30, or any combination of r and F in one car, Figs. 31 and 32; second, interior transverse bracing or trussing is provided at the proper points connected to any 70 or all of the longitudinal trusses. Figs. 28 to 32, inclusive, show the same in connection with the interior longitudinal trusses, F, the space above and below the passage-ways being suitably trussed to transmit the web-shears. Figs. 20 to 26, inclusive, show corner-brackets o' on one side, and Figs. 24 to 27, inclusive, show diagonal members o for one-half of each view only. Figs. 20, 24, 25, and 27 show the posts s² of the trusses B designed as 80 girders, also in a transverse direction, all to resist lateral or transverse displacement and thereby equalize any impacts exerted against the structure. In Figs. 20 to 32, inclusive, the floor portion is transversely constructed 85 by trussing and bracing, which will be understood on inspection.

The floor-line C may be horizontal or any other shape, either longitudinally or transversely, or both combined, but not required 90 to be necessarily on the same level of the bottom chords s' of girders B, or that of r or F. This floor-level C may be longitudinally (also statically) trussed, as well as the bottom chords of the above-referred-to girders in the 95 same direction, as fully described in my above-referred-to patent application and therein marked D for the latter. All these trusses C and D, and part of B, F, and r, form in themselves, with the vibration-trussing r' and with parts of each car-body end, a complete 100 auxiliary lower or floor body or frame externally and internally, and as a whole statically trussed.

I also construct an overhead or roof auxiliary body or frame externally and internally, and as a whole statically constructed, as fully described in my Patent No. 384,225, and consisting, internally, of statically-constructed 110 transverse vertical roof-trusses q, with rigid 115 and non-adjustable web members throughout their entire length, externally formed by the exterior longitudinal roof-trussing along the rafters q⁴ of the above transverse roof-trusses q and the interior longitudinal trussing through 120 the top chords s of the trusses B along the bottom chord q' of the same roof-trusses q. Any of the combinations or modifications referred to in my above-named patent also apply here. Any of the herein-described single-deck cars, if constructed of sufficiently 125 uniform or variable height, can be used as a double or multiple deck car by adding the upper floor, U, at a suitable height with the necessary truss-work to support it. This upper floor may have also longitudinal interior girders r, or such as F, extending any distance or all the way to the upper floor, U, or any distance or all the way to the roof, or be-

tween the upper floor and the roof any distance or all the way, or any combination of any or all of these various kinds may be used in one car. It may have transverse girders

5 r' , which may also extend any distance or all the way to the upper floor, U, or any distance or all the way to the roof, or between the upper floor and the roof, any distance or all the way, or any combination of any or all of those 10 in one car.

Access or exit can be had through doors or openings placed in any or all of the outer faces and the floors; but care should be exercised that these various openings are not located 15 directly over each other, or not at in the same transverse section to allow of sufficient trussing with diagonals for the various web-shear transmissions; or by stairs, steps, or inclines T intercourse can be had internally between 20 the various decks. Any combination of these outer and inner means of intercourse can be applied singly, or any or all combined. As shown, T is placed in a longitudinal direction; but any other direction will do as well, and 25 they can be located anywhere in the car, centrally or at the ends or otherwise, and they may be constructed circular or otherwise. Fig. 19 shows a truss-work suitable for window-openings for each deck in the spaces z, 30 although any of the other herein-shown trusses may be used instead. While Fig. 18 may be used, preferably, for large door and other openings, there may be more or less of them in number, and they may be located differently. 35 In this case the stairs, steps, or inclines T may be omitted.

The main floor C may have stairs or steps to facilitate reaching the central part of the car, Fig. 18, or it may be inclined, Fig. 19.

40 I am aware that formerly wooden cars were built having increased depth at the center with the outer sides extending downward between the two trucks and forming a lower horizontal floor. The top and bottom of the 45 car-body sides being horizontal, they do not form either trusses proper or statically-constructed trusses, nor is such a construction described in my patent referred to.

I am also aware that cars having increased 50 central depth exist with partly-trussed sides, the bottom chords of which are not continuous, and which are not therefore statically trussed, and do not constitute a statically-trussed car-body.

55 I am also aware of the existence of double-deck cars, but not of statically-trussed double-deck cars, as herein disclosed and claimed.

I am also aware that compartment-cars exist having loose and removable boxes with 60 hinged doors adapted to facilitate loading and unloading. Such cars, however, consist merely of platforms having hog-chained vertical girders, and do not receive any additional strength from the removable boxes, 65 there being no trussed connection between said boxes and the frame.

I am also aware of the use of combined double-deck sleeping and dining cars, which, however, do not possess as an element of their construction any trussed frame-work.

70

Having thus described my invention, what I claim, and desire to secure by Letters Patent of the United States, is—

1. A railway-car frame having two or more longitudinal trusses or girders extending 75 throughout the length of the car, having increased depth at or near the center of the car, and connected together at or near their upper and lower chords by trussed girders adapted to resist lateral strains, the whole being joined 80 together to form a statically-trussed frame, substantially as shown and described.

2. A railway-car frame consisting of two or more longitudinal supporting trusses or girders having increased depth at or near the center of the car, connected at or near the top and bottom by longitudinal trusses or girders, with one or more intermediate cross or tie trusses or bracing uniting said longitudinal trusses, so as to form a solid or statically- 90 constructed structure, substantially as described.

3. A railway-car frame consisting of an external skeleton body having vertical longitudinal trusses of increased center depth, with 95 one or more vertical transverse statically-constructed overhead roof-trusses having rigid and non-adjustable web members throughout their entire length, substantially as described.

4. A railway-car frame consisting of an external skeleton body having vertical longitudinal trusses of increased depth between the truck-supports, with one or more interior transverse vibration-trusses and one or more vertical transverse statically-constructed 105 overhead roof-trusses having rigid and non-adjustable web-members throughout their entire length, substantially as described.

5. A railway-car frame consisting of an external skeleton body whose vertical longitudinal trusses are of increased depth between the truck-supports, with one or more interior longitudinal trusses and one or more vertical transverse statically-constructed overhead 110 roof-trusses having rigid and non-adjustable 115 web members throughout their whole length, substantially as described.

6. A railway-car frame consisting of an external skeleton body, with vertical longitudinal trusses of increased depth between the truck-supports, and one or more interior longitudinal trusses, and one or more interior transverse vibration-trusses, and one or more vertical transverse statically-constructed overhead 120 roof-trusses having rigid and non-adjustable web members throughout their whole length, substantially as described.

7. A railway-car frame having four or more longitudinal external members, any of which may be of irregular shape, with diagonal and 130 normal members connecting the sides of said frame to said longitudinal members, and di-

- agonal and normal members connecting the top and bottom of such frame to said longitudinal members, substantially as described.
8. A railway-car frame having normal and diagonal braces in its side faces, the latter of variable depth, in combination with diagonal and normal braces in its top and bottom faces, and knee-braces between the sides and top and bottom faces, substantially as described.
10. 9. A railway-car frame consisting of trussed lateral top, bottom, and side faces, the latter of variable depth, in combination with a trussed - roof - supporting frame or auxiliary body, substantially as described.
15. 10. A railway - car frame consisting of trussed lateral top, bottom, and side faces, the latter of variable depth, in combination with a trussed-floor-supporting frame or auxiliary body, substantially as described.
20. 11. A railway - car frame consisting of trussed lateral top, bottom, and side faces, the latter of variable depth, in combination with a trussed floor, and also a trussed-roof-supporting frame forming each an auxiliary body, substantially as described.
25. 12. A statically-constructed railway - car frame wherein any or all exterior or interior faces are each constructed of two or more statically-constructed trusses integrally connected together for each face, so as to form one truss of variable depth and having openings for windows or doors, substantially as described.
13. A statically-constructed railway - car frame having longitudinal girders with a diminished depth at their ends, in combination with top and bottom chords, the arrangement being such as to resist collision strains more evenly. 35
14. A statically-constructed railway - car frame containing two or more statically-trussed floor-frames, each integrally connected therewith and each constituting the floor-support, substantially as described. 40
15. A statically-constructed railway - car frame containing one or more trussed floor-frames integrally connected therewith, each constituting a floor-support and any or all inclined in any one or various directions to assist in the discharge of the load, substantially 45 as described. 50
16. A statically-constructed railway - car frame containing one or more trussed floor-frames integrally connected therewith, having longitudinal trusses, their greatest depth being at or near the center of the car, while the top chords of the floor-girders which sustain the floor are inclined, substantially as described. 55
